UNITED STATES PATENT OFFICE.

HENRY H. LAW, OF GLOUCESTER, NEW JERSEY.

IMPROVEMENT IN SHUTTLE-BINDER-ACTUATING MECHANISMS.

Specification forming part of Letters Patent No. 127,776, dated June 11, 1872.

Specification describing a new and Improved Shuttle-Binder, invented by HENRY H. LAW, of Gloucester, in the county of Camden and State of New Jersey.

My invention consists of a spring-presser on one of the lathe-swords, and an arm on one of the rods connecting the lathe with the crank-shaft, so arranged that when the cranks are down and the shuttle is in a box the said arm will act on the presser, which will thereby act on an arm of the protecting-rod and cause arms thereon to bear on the shuttle binding-levers in the sides of the boxes, and confine the shuttle until the cranks rise and release the said presser. The arms of the protecting-rod are then forced away from the shuttle-boxes to relieve the shuttle by other springs acting on the said protecting-rod.

Figure 1 is a front elevation of the lathe of a loom and part of the swords. Fig. 2 is a top view of the same, also the rods connecting the lathe with the cranks; and Fig. 3 is a transverse section on the line $\alpha\alpha$ of Fig. 2.

Similar letters of reference indicate corresponding parts.

A represents the lathe-beam; B, the shuttle-boxes; C, the shuttle binding-levers; D, the protecting-rod; E, the rods connecting the lathe with the crank-shaft; and F, the swords. The shuttle binding-levers are pivoted in the sides of the boxes in the ordinary way, and the rod D has arms G acting on them as in other looms. For actuating the said rod I propose to have an arm, H, projecting downward from one of

the rods E, in front of and near one of the swords, as clearly shown in Fig. 3, to come in contact with a pusher, I, fixed in a hole through the sword, so as to project far enough at the rear to be so acted on, and projecting from the front side, and carrying a spring, J, in a socket in its end, which spring is connected to the arm K of the rod D, so as to press said arm outward by a yielding pressure, and thereby force the upper arms G against the levers C. This operation takes place when the cranks are moving down, which is at the same time that the shuttle is driven into one of the boxes, and it is retained thereby until the cranks rise enough to carry the arm H away from the pusher so that it releases the arm K and rod D, which is then turned by a spring, L, which throws the arms G back from the levers C. This takes place just previous to the time of throwing the shuttle, which is done just after the cranks rise and the arm H is released from the push-pin.

Having thus described my invention, I claim as new and desire to secure by Letters Patent—

The combination, with the protector-rod D and the arms G and K, of a spring-pusher on the lathe sword, and an arm, H, on the connecting-rod E, all constructed and operating substantially as specified.

HENRY H. LAW.
